(57) **CLAIM**

The ornamental design for a rear fairing, as shown and described.

DESCRIPTION

FIG. 1 is a perspective view of a rear fairing showing our new design;

FIG. 2 is a front view of the rear fairing shown in FIG. 1;
FIG. 3 is top view of the rear fairing shown in FIG. 1;
FIG. 4 is a bottom front view of the rear fairing shown in FIG. 1;

FIG. 5 is a left side view of the rear fairing shown in FIG. 1; and,

FIG. 6 is a right side view of the rear fairing shown in FIG. 1.

The broken lines shown in the figures represent portions of the rear fairing that form no part of the claimed design.

FIGS. 1-6 illustrate a first embodiment of our novel design for use on one side of a vehicle. Our novel design also includes a second embodiment suitable for use on the opposite side of a vehicle, which is mirror symmetrical to FIGS. 1-6 and therefore not separately illustrated.

1 Claim, 4 Drawing Sheets
